PRESSURE MECHANISM FOR FASTENING-
INSERTING MACHINESJohn F. Standish, Winthrop, Mass., assignor to
United Shoe Machinery Corporation, Paterson,
N. J., a corporation of New Jersey

Application January 11, 1938, Serial No. 184,444

15 Claims. (Cl. 1—32)

My invention relates to mechanism by which work is held in place upon its support to receive fastenings. It is herein disclosed in connection with apparatus for attaching heels to shoes by nails driven through the heel-seat of a shoe into an applied heel.

In heelng shoes, a well-known and highly efficient hold-down mechanism utilizes a pressure-compensating arrangement in which the tread and rear heel-abutment members are carried by slides connected by gearing, which, as one member engages its portion of the heel, moves the other into engagement and thereafter tends to equalize the forces applied over the two areas. Conditions are sometimes encountered in which this compensating connection introduces difficulties. The nails driven at the rear of a heel having considerable forward pitch, will act upon the horizontally extended rear portion through a leverage which exerts an upward displacing effect stronger than that existing toward the breast of the heel. This raises the rear abutment and, through the connecting gearing, lowers the tread-abutment. The downward force exerted by the latter may crush the heel or deform its covering. It is an object of this invention to guard against this application of unequal pressure.

In accomplishing the above result, I employ pressure mechanism having a carrier member, with work-engaging members, as tread and rear abutments, movable relatively to each other upon the carrier, for example in the manner previously indicated. Thereafter, these engaging members together and the carrier member are also movable relatively, and there is means made effective in this last-mentioned movement for locking them against the relative movement between them. When this is done, the force which they exert is uniform. To produce this effect, a connecting member between the work-engaging members is mounted for a movement of translation upon the carrier member, and by relative bodily movement between it and the carrier member the lock is applied, as by a brake, to the connecting member and thus to both work-engaging members. To determine when this locking action shall be initiated, there is means, as a spring or springs, for resisting the movement of translation and means for varying the resistance. In the particular embodiment of the invention disclosed herein, the work-engaging members are abutments which respectively contact with the tread and rear surfaces of a heel to be attached, these abutments being mounted upon slides movable upon the carrier member. Gearing, includ-

ing a pinion, joins the slides, and this pinion rotates in bearings movable with respect to the carrier. With the pinion, a disk or disks is rotatable, these being normally spaced from brake members, so the pinion is free to turn and produce the relative movement between the slides, together with the abutments. When, however, the bearings are displaced, as by relative movement of the slides together and the carrier, the brake members engage the disks, and the movement of the abutments relatively to each other is rendered impossible. Preferably, a balanced action is produced by employing two of the locking disks at opposite sides of the pinion, these being shown as having peripheries which are complementary to locking depressions in the carrier and provided with outwardly converging walls. The entrance of the disks into the depressions may serve to retain them upon projections from the pinion, and upon which they are held against rotation, though free to move longitudinally thereon. The assembling of the elements is thereby facilitated.

In the accompanying drawing,

Fig. 1 illustrates a particular form of the invention in broken side elevation;

Fig. 2 is a partial, central, transverse, vertical section with the lock applied, and

Fig. 3 shows, similarly, the more essential elements with the lock freed.

In the drawing appear portions of a commercial form of machine for attaching heels by inside nailing. This includes a jack 10 with one of its drivers 12, by which nails N are inserted, and an opposed vertically reciprocatory pressure-head 14 in which a carrier-slide 16 is horizontally movable in ways 18 extending from front to rear of the machine. Adjustment of the carrier in the ways may be effected by a screw 20. Guides for vertical movement in the carrier are spaced slides 22, 24. These slides have respectively mounted at their lower extremities an abutment in the form of a plate 26 arranged for contact with the tread-surface of a heel H, which has been applied to a shoe S supported on the jack 10, and an abutment furnished by a fork 28 for engagement with the rear of the heel. The mounting and manner of adjustment of the abutments may be as usual. Upon the adjacent faces of the slides 22 and 24 are racks 30, with both of which meshes an intermediate pinion 32. Assuming the axis of the pinion to be at rest, its effect, when one of the slides 22 or 24 is moved, is to shift the other in the opposite direction. The slides are biased by a tension-spring 34 join-

ing the rear slide to the carrier. This holds the tread-abutment normally lowered to a point determined by the height of an adjustable stop-screw 36, with which a portion of the rear abutments contacts when elevated by the spring. When thus organized, as the head 14 is lowered the abutment 26 will first engage the tread-surface of the heel being operated upon. The travel of the abutment 26 being arrested, the pinion 10 would be rotated in the continued downward movement of the head to lower the abutment 28 until this, too, engages the heel. Thereafter, as further pressure is exerted, there being no displacing force, the two abutments would bear 15 equally. The balance of forces may, however, be disturbed, as already pointed out, and to prevent this, I have improved the mechanism in the following manner.

Instead of having the axis of the pinion fixed 20 upon the carrier, it is arranged for movement longitudinally of the slides 22 and 24. At its opposite sides are axial projections 40, 40, which receive circular disks 42, 42. The ends of the projections are shown as squared at 46, 46 and thus hold against rotation the hubs 48 of the disks. The exterior inner portions of the disk-hubs turn in bearing-blocks 52, 52 arranged for vertical movement of translation in ways in the carrier 16. The pinion and disks may be held 25 down, with the bearing-blocks resting upon surfaces 54, 54 of the carrier, by springs 56, 56 interposed between the blocks and screws 58, by which the force exerted on the springs may be varied. The periphery 60 of each disk is wedge-shaped, converging outwardly, and when the 30 pinion-and-disk-assembly is held against movement as the carrier 16 descends, the upper portion of the peripheries of the disks are engaged by walls of complementary segmental depressions 35 62 in the carrier. There may thus be applied two brake devices to hold the pinion against rotation. A movable cover-plate 64 secured in place by screws 66 at one side of the carrier, allows the pinion-disk-assembly with its bearing-blocks to 40 be positioned. With the disk opposite the cover-plate and its bearing-block in place upon the carrier, the periphery of the disk being in the depression 62, the pinion carrying the other bearing and disk may be applied, and the cover- 45 plate secured upon the carrier. Displacement of the disks longitudinally of the pinion-projections is prevented by their entrance into the depressions. The springs 56 may be introduced through 50 the openings for the screws 58.

When the operator has jacked a shoe S, applied 55 a heel H to its heel-seat and lowered the pressure-head 14, the abutment 26 first contacts with the tread-surface of the heel, and then causes the lowering of the abutment 28 to engage the rear of the heel through the racks 30 and the pinion 32. At this time, the springs 56 hold the axis of the pinion and the carrier against relative movement, the elements being as appears in Fig. 3. The adjustment of the screws 58 is pref- 60 erably such that the abutment 28 engages the heel before this relative movement occurs. When, however, both abutments are held by the heel, downward movement of the carrier continues to produce a relative movement of translation be- 65 tween the pinion-disk-assembly and said carrier, without rotation of the pinion. Since the normal clearance between the peripheries of the disks and the walls of the depressions is but slight, the opposite inclined surfaces are forced together 70 75 (Fig. 2), effectively locking the pinion against

rotation. As a result of this, the relation of the two abutments to the heel which was established when both arrived in contact with it, is maintained, and the pressure exerted by them upon the heel, and the resistance they offer to displacement, remains the same throughout the nail-inserting operation. The heel is consequently securely held without danger of injury by the application of unbalanced forces. Upon release of the pressure-head, the elements which it supports are returned to their initial positions by the springs 34 and 56.

Having described my invention, what I claim as new and desire to secure by Letters Patent of the United States is:

1. Pressure mechanism for fastening-inserting machines comprising a carrier member, heel-engaging members movable relatively to each other upon the carrier and thereafter the engaging members together and the carrier being movable relatively, and means made effective upon the last-mentioned movement for locking the engaging members against movement relatively to each other.

2. Pressure mechanism for fastening-inserting machines comprising a carrier member, heel-engaging members movable relatively to each other in opposite directions upon the carrier and thereafter the engaging members together and the carrier being movable relatively in the same direction, and means made effective upon the last-mentioned movement for locking the engaging members against movement relatively to each other.

3. Pressure mechanism for fastening-inserting machines comprising a carrier member, work-engaging members movable upon the carrier member, a connecting member for communicating movement from one of the work-engaging members to the other and itself mounted for movement of translation relatively to the carrier member, and means acting upon said movement of translation for locking the connecting member against the communication of movement between the engaging members.

4. Pressure mechanism for fastening-inserting machines comprising a carrier member, work-engaging members movable upon the carrier member, a connecting member for communicating movement from one of the work-engaging members to the other and itself mounted for movement of translation relatively to the carrier member, means acting upon said movement of translation for locking the connecting member against the communication of movement between the engaging members, means for resisting the movement of translation, and means arranged to vary the resistance.

5. Pressure mechanism for fastening-inserting machines comprising a carrier member, work-engaging members movable upon the carrier member, a connecting member for the engaging members rotatable between said engaging members, bearings for the connecting member and between which and the carrier member there may be relative movement, and a brake member acting on the connecting member upon such relative movement.

6. Pressure mechanism for fastening-inserting machines comprising a carrier member, work-engaging members movable upon the carrier member, a connecting member for the engaging members rotatable between said engaging members, bearings for the connecting member and between which and the carrier member there may be rela- 75

tive movement, springs resisting such movement, and a brake member acting on the connecting member upon such relative movement.

7. In a heel-attaching machine, a carrier, two slides movable upon the carrier, a heel-engaging member mounted upon each slide, gearing connecting the slides and including a pinion, bearings for the pinion guided upon the carrier, a disk rotatable with the pinion, and a brake member from which the disk is normally spaced, said brake member being engaged upon relative movement between the carrier and bearings.

8. In a heel-attaching machine, a carrier, two slides movable upon the carrier, a heel-engaging member mounted upon each slide, gearing connecting the slides and including a pinion, bearings for the pinion guided upon the carrier, a disk rotatable with the pinion, a brake member co-operating with the disk, and a spring urging the disk away from the brake member.

9. In a heel-attaching machine, a carrier, two slides movable upon the carrier, a heel-engaging member mounted upon each slide, gearing connecting the slides and including a pinion, bearings for the pinion guided upon the carrier, a disk rotatable with the pinion, a brake member co-operating with the disk, a spring urging the disk away from the brake member, and means arranged to vary the force exerted upon the disk by the spring.

10. In a heel-attaching machine, a carrier provided with brake-surfaces, two slides movable upon the carrier and having rack-teeth, a tread-abutment mounted upon one slide, a rear abutment mounted upon the other slide, bearings movable longitudinally of the slides at opposite sides of the carrier, a pinion meshing with the rack-teeth and having projections rotatable in the bearings, and disks rotatable with the projections at opposite sides of the pinion for engagement with the brake-surfaces upon relative movement between the carrier and bearings.

11. In a heel-attaching machine, a carrier provided with brake-surfaces, two slides movable upon the carrier and having rack-teeth, a tread-abutment mounted upon one slide, a rear abutment mounted upon the other slide, bearings movable longitudinally of the slides at opposite sides of the carrier, a pinion meshing with the rack-teeth and having projections rotatable in the bearings, and disks rotatable with the projections at opposite sides of the pinion for engagement with the brake-surfaces upon relative

movement between the carrier and bearings, the disks being retained upon the pinion-projections by said brake-surfaces.

12. In a heel-attaching machine, a carrier provided with segmental depressions having walls converging outwardly, two slides movable upon the carrier and each supporting a heel-abutment, said slides having adjacent rack-teeth, bearings guided in the carrier at opposite sides of the rack-teeth, a pinion meshing with the rack-teeth and provided with projections rotatable in the bearings, and disks rotatable by the projections and having their peripheries entering the carrier-depressions and formed complementally thereto.

13. In a heel-attaching machine, a carrier provided with segmental depressions having walls converging outwardly, two slides movable upon the carrier and each supporting a heel-abutment, said slides having adjacent rack-teeth, bearings guided in the carrier at opposite sides of the rack-teeth, screws threaded through the carrier, springs interposed between the screws and the bearings, a pinion meshing with the rack-teeth and provided with projections rotatable in the bearings, and disks rotatable by the projections and having their peripheries entering the carrier-depressions and formed complementally thereto.

14. In a heel-attaching machine, a carrier provided with segmental depressions having walls converging outwardly, two slides movable upon the carrier and each supporting a heel-abutment, said slides having adjacent rack-teeth, bearings guided in the carrier at opposite sides of the rack-teeth, a pinion meshing with the rack-teeth and provided with projections rotatable in the bearings, and disks movable longitudinally of the projections but compelled to rotate therewith, said disks being journaled in the bearings and having their peripheries entering the carrier-depressions and formed complementally thereto.

15. Pressure mechanism for fastening-inserting machines comprising a movable carrier, two heel-engaging members movable upon the carrier, a connecting member for communicating the movement of one of the engaging members to the other and being rotatable about an axis with respect to which the carrier may move, and means made effective upon such movement of the carrier for locking the connecting member against its communication of movement between the engaging members.

JOHN F. STANDISH.
